UNITED STATES PATENT OFFICE

CHARLES E. HUFFMAN, OF SUTTON, NEBRASKA

BOX CLOSURE

Application filed October 14, 1929. Serial No. 399,550.

This invention relates to box closures and more particularly to closures for paper file boxes.

A primary object of the invention is to provide a closure of this character which is simple in construction, holds securely, unfastens with a slight lift, and which will prevent bulging of the box when crowded.

Another object of the invention is to so construct the closure which combines with its fastening features a non-spill feature without the use of glue or glued fabrics and which renders the contents of the file easily and quickly accessible and which permits files equipped with such closures to be stacked and pressure exerted on them without unlocking the fasteners.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a perspective view of a box file equipped with this closure and shown in closed position;

Fig. 2 is a similar view with the closure shown partly open, parts being broken away for convenience in illustration; and

Fig. 3 is a detail transverse vertical section through one end of the box or file equipped with this closure.

In the embodiment illustrated a box equipped with this invention is preferably made from fiber board or card board of suitable weight formed by slitting and folding the various parts together as is usual in forming boxes of this character. The lid or top of the box is preferably formed by slitting the material longitudinally to provide two flaps 2 and 3 which when closed will have their slit edges abutting and the closure constituting this invention is designed for completely closing the seam between the inner edges of these flaps and for firmly holding them in their closed position.

Secured to the upper face of the flap 3 along the inner edge thereof is a strip 10 preferably constructed from sheet steel of

very light gauge or from any other suitable material. This seam closing strip 10 is riveted or otherwise secured to the flap 3 and projects beyond the edge thereof so that when this flap is closed the strip will overlie the edge of flap 2 and thus render the center seam dust and vermin proof. This seam closing strip 10 is of a length greater than the length of the flap 3 to which it is applied and has the ends thereof folded inwardly and secured to provide loops 11 and 12 for securing to the strip metal loops 13 and 14 here shown rectangular in form and which are designed to provide a flexible joint between the seam closing strip 10 and the end closing strips 15 and 16. These end strips 15 and 16 are preferably made of light gauge steel, heavy canvas or leather or any other suitable material and each has one end engaged with its cooperating loop 13 or 14 and stitched or otherwise secured to provide a connection 17. These strips 15 and 16 are exactly alike so that one only will be described in detail. Near the free end of strip 16 is attached a fastener socket 18 such as is used in snap fasteners and which is designed to cooperate with a stud 20 secured to the end 4 of the box at a point about midway the width thereof. The flexibly connected strips 10 and 16 eliminate tension caused by packing or any handling and hence avoids all danger of the fastener becoming unlocked.

To avoid spreading of the center seam and bulging of the end members 4 incident to overpacking of the boxes or files, anti-spread devices are applied to each end and both being exactly alike hence one only is shown and described and which is numbered generally 25. This anti-spreader consists of a small plate of thin metal 26 having an opening 27 to fit over the stud 20 as shown clearly in Fig. 2. This plate 26 also has a transversely extending opening or slot 28. A strip of thin metal or strong cloth 29 is looped through the slot 28 and secured by stitching or otherwise. This strip which may extend the full length of the box or only a part thereof as shown is secured to the flap 2 along the free edge by rivets and is designed

to be overlapped by the seam closing strip 10 when the flaps 2 and 3 are closed.

In the use of this closure when flap 2 is shut down as shown in Fig. 2 the end of the plate 26 is engaged with the stud 20 before the fastener member 16 is snapped over said stud. The flap 3 is then shut down and the flap fastener socket 18 engaged with the stud 20 at each end of the box which will securely hold the box closed and the contents effectively protected.

To open the box the projecting end of the strip 16 is grasped by the fingers of the user and lifted to release the socket from the stud 20, it being of course understood that this operation is carried out at both ends of the box and the flap 3 may be then raised to afford access to the interior. If desired to open flap 2 the plate 26 is disengaged from stud 20 and this flap may be opened up in a well known manner.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

1. In combination a box having a two flap lid for closing the top of the box except for a slit at the meeting edges of the flap, a strip secured to the edge of one flap to project over the edge of the other flap and cover the slit between the flaps, members depending from the extremities of said strip and loosely connected therewith to avoid tension being exerted on said members, said members having fastener elements, complementary fastener elements carried by the box ends for detachable engagement with the fastener elements of said depending members, and means carried by one of said flaps and having means for engaging the fastener elements on the ends of the box for holding said box flaps against spreading at the center seam and the bulging of the box ends.

2. In combination a box having a two flap lid for closing the top of the box except for a slit at the meeting edges of the flaps, a strip secured to the edge of one flap to project over the edge of the other flap and cover the slit between the flaps, members depending from the extremities of said strip and loosely connected therewith to avoid tension being exerted on said members, said members having fastener elements, complementary fastener elements carried by the box ends for detachable engagement with the fastener elements of said depending members, and means for holding said box flaps against spreading, said means comprising apertured plates carried by the underlying flap and adapted to

engage the fastener elements on the ends of the box.

3. In combination a box having a two flap lid for closing the top of the box except for a slit at the meeting edges of the flaps, a strip secured to the edge of one flap to project over the edge of the other flap and cover the slit between the flaps, members depending from the extremities of said strip and loosely connected therewith to avoid tension being exerted on said members, strips carried by the ends of said underlying flap and having plates loosely mounted on the extremities thereof, fastener elements carried by the box ends and adapted to be engaged by said plates, and members depending from the first mentioned strip and adapted to engage the fastener elements on the box ends for holding the flaps in closed position and to prevent spreading thereof.
